COMPUTING-HEAD-SETTING MECHANISM.

1,244,574.

Specification of Letters Patent.

Patented Oct. 30, 1917.

Application filed November 2, 1911. Serial No. 658,119.

To all whom it may concern:

Be it known that I, WALTER WRIGHT, a citizen of the United States, residing in New York city, in the county of New York 5 and State of New York, have invented certain new and useful Improvements in Computing-Head-Setting Mechanism, of which the following is a specification.

This invention relates to hand-automatic 10 computing-head setting mechanism of a type useful in connection with the Underwood-Wright combined typewriting and computing machines such as those shown in my Patent No. 1,162,730, and in application No. 15 543,603 filed February 12, 1910, by Gustave O. Degener and myself, and in my applications No. 631,115, filed June 3, 1911, and No. 574,813, filed August 1, 1910.

In certain types of combined typewriting 20 and computing work, it is desired to repeat a predetermined sequence of operations over and over again. For example, it may be desired to keep a bank account, wherein the date is written out, the balance of the day 25 before carried forward, the amount deposited added to this balance, to give the cash on hand and the total of all the checks drawn against this cash on hand summed up and deducted from the cash on hand, so as to 30 give the balance to be carried forward to the next day.

Now if above computation were carried on, and assuming each day occupied a line, it would be necessary to repeatedly shift one or 35 more computing heads to their several states of adding, neutral and subtracting a number of times each line, according to the sequence of the various portions of the computation carried on.

Where a number of computing heads are 40 used, and frequent changes in each computing head required during a single line, as in the above problem, the operation becomes tedious, and also is open to the danger of 45 having mistakes made by a wrong shift of one of the computing heads.

It is therefore an object of this invention 50 to provide an automatic hand shift which will change the state of one or more computing heads, according to a predetermined sequence of operations to be carried on by the simple mechanical shifting of a lever at each point where it is necessary to make

a change in the character of the work being done by the computing heads.

In the embodiment with which this invention is illustrated, a computing machine of the Underwood-Wright type is used, in which the master wheel of each computing head is driven a predetermined amount from 55 a source of power, which amount is controlled by an escapement mechanism, and depends on the particular numeral key actuated. The master wheel of each head is connected to the source of power by means 60 of a gearing, which includes a clutching mechanism capable of reversing, so as to drive in either direction, and also capable of occupying a neutral position wherein the master wheel will not be driven at all. Tens- 65 carrying mechanism for each computing head is also driven from the source of power, and also has a controlling mechanism shift- 70 able so as to drive in both directions, and also so as not to drive at all. The controlling 75 mechanism of each master wheel and the tens-carrying mechanism are operable by the movement of a composite shifting lever.

To obtain the automatic shift of all of the 80 computing heads, so that the sequence of operations will be mechanically certain, a shaft is shifted so that it will swing all of 85 the clutching mechanisms which are operated by individual levers to one extremity of their motion, and this shaft, on its return movement, after having been rotated a predetermined amount, will shift such of the levers back, as it is desired to bring the corresponding computing head to some other 90 state than that corresponding to the extreme movement in the first direction, just mentioned. As shown, the levers are first shifted down, so that they occupy a position corresponding to the adding state of their respective computing heads, and they are shifted back by a series of position tappets, which are brought successively, by the rotation of the shaft at each actuation thereof, into co- 95 operative relation with the levers. These tappets are of various effective magnitudes, 100 depending on the particular character of the work desired at the instant when they are in co-operation with the levers. That is to say, if it is desired to add, the levers, being in adding position, would not need any shifting, and therefore no tappet would be pro-

55

vided at this point. If it is desired that either one of the computing heads should remain neutral, the tappet to actuate the lever at this instant would be only of sufficient effective magnitude to bring the lever back to its intermediate or neutral position. If, however, it is desired to subtract, the tappet would be of greater effective magnitude, so as to throw the lever to the other extreme of its swing, corresponding to the subtracting state of its computing head. The shaft is operated by an actuator or lever in such a manner that it will be swung downwardly before rotating, and then held in its lowermost position while being rotated and subsequently brought back to its original position after it has been rotated a sufficient amount to bring the next position controlling tappets in coöperative juxtaposition with the shifting levers. A complete throw lock may be provided to prevent the partial swing and return of the actuator.

Other features and advantages will hereinafter appear.

Referring to the drawings,

Figure 1 is a fragmentary view in side elevation.

Fig. 2 is a vertical section, showing the controlling shaft in its normal or raised position.

Fig. 3 is a view similar to Fig. 2, showing the controlling shaft in its lowermost position.

Fig. 4 is a detail view of the actuator for the shaft and the mechanism connected thereto, showing the actuator in its normal unoperated position.

Fig. 5 is a view of certain of the parts shown in Fig. 4, showing the actuator after it has moved a sufficient amount to depress the controlling shaft, but not a sufficient amount to rotate said shaft.

Fig. 6 is a detail perspective view of one of the holders for the controlling position tappets.

Fig. 7 is a section showing certain details of an adding head.

Fig. 8 is a detail perspective view of the throwout for the lever latches.

Fig. 9 is an enlarged section, showing the method of securing the position tappets in place.

Fig. 10 is a detached perspective view of one of the position tappets.

Fig. 11 is a perspective view of the cam actuated lever for reciprocating the controlling shaft.

Fig. 12 is a developed view, showing the arrangement of one series of position tappets for controlling a given cycle of operations of one of the computing heads.

Fig. 13 is a side view of the computing heads, showing the connection to the typewriter carriage.

Referring more particularly to the sepa-

rate parts of this invention as embodied in the form shown in the drawings, 1 indicates a motor which drives through a slip clutch (not shown) a bevel gear 2 meshing with a gear 3 on a shaft 4. The shaft 4 is provided with a bevel gear 5 meshing with a controlling bevel gear 6, which is mounted on a shaft 7, the rotation of which is prevented by an escapement mechanism 8 controlled by the numeral keys in such a manner as to permit a rotation of the shaft 7, at the actuation of a numeral key, an extent proportionate to the particular numeral key struck, the slip clutch (not shown) permitting the rotation of the motor without actuating the other mechanism. This structure is more fully described in said prior application No. 543,603, filed February 12, 1910, jointly by Gustave O. Degener and myself.

The bevel gear 6 has also meshing therewith a bevel gear 9, which is mounted on a shaft 10, so as to rotate a bevel gear 11 at its other end, which meshes with a bevel gear 12 on a vertical shaft 13. The shaft 13 is provided with a plurality of pairs of bevel gears, one pair for each of the computing heads 14 and 15. These gears are indicated by the numerals 16 and 17, and 18 and 19. The members of each pair are faced in opposite directions, and both of them mesh with gears 20 and 21, so as to be capable, when they are rotated, of driving these gears 20 and 21 in opposite directions.

The gears 16 to 19, however, are loosely mounted on the shaft 13, but capable of being connected thereto by means of shift clutches 22 and 23, which have teeth on each end capable of engaging with corresponding teeth provided in the inwardly facing sides of the gears 16 to 19, so as to connect either one of each pair in driven relation with the shaft 13. These clutches can also assume an intermediate neutral position in which neither of the members of each pair of gears is connected in driving relation to the shaft 13. Each of the clutches 22 and 23 is provided with a groove into which pins 24 on shifting levers 25 and 26 enter. These shifting levers project from the front of the machine, so that they can be manipulated to control the position of each clutch. For the purpose of holding each of these levers in any adjusted position, there are provided spring latches 27 and 28, which engage in one of three notches 29 provided on an extension of each of the levers 25 and 26. Springs 30 tend to draw the shift levers 25 and 26 to their lowermost position corresponding to adding.

It will thus be seen that the direction of rotation of the gears 20 and 21 can be controlled separately very easily. These gears are secured to master wheel shafts 31, which, as will be seen by reference to Fig. 13c

7, are squared, so as to permit arbors 32 to be splined thereon, whereby the shafts may be caused to rotate master wheels 33 secured to these arbors, and yet permit a relative 5 movement between the master wheels, and a series of computing wheels 34, so as to bring them successively in engagement with the internal gears formed by the inwardly projecting teeth 35 provided on these computing 10 wheels. The computing wheels 34 are also provided with external teeth forming external gears 36, which mesh with gears 37 carrying dial wheels 38 adapted to exhibit the result of the computation carried on by 15 the computing head. This mechanism is shown more clearly and described more fully in prior applications No. 543,603 and No. 631,115, above mentioned.

The relative movement above referred to, 20 between the master wheels and the computing wheels may be brought about in a manner usual in this art. As is well known, either the master wheels may be moved through the computing wheels, or the computing 25 wheels may be moved over the master wheels. In order to produce this relative movement, I have shown a connection between the master wheels and the typewriter carriage (Fig. 13). The connection in this instance 30 comprises a frame 103 and a frame 103^a, one frame for each master wheel, said frames being connected to the typewriter carriage 104, through the medium of a connecting lever 105, a hook 106, and a tappet 35 107 carried on a bar 108 forming part of the typewriter carriage.

In addition to driving the master wheels, the shaft 4 also drives in each computing head the tens-carrying mechanism, indicated 40 at 39. This mechanism is described in said application No. 543,603, and depends for its actuation on the rotation and direction of rotation of a rubber roller 40 secured to a shaft 41, there being of course one of these 45 rubber rollers provided in the case of each computing head. The shafts 41 are driven by bevel gears 42 and 43 similar to those of the master wheel driving shafts. These bevel gears 42 and 43 mesh with pairs of 50 oppositely disposed bevel gears, which are loosely mounted on a shaft 44, so that when any one of these bevel gears is connected to the shaft 44, it will drive one of the bevel 55 gears 42 or 43 in a direction corresponding to the way in which it faces. The members of the pairs of bevel gears are indicated by the numerals 45, 46, 47 and 48.

To control the connection of the members of the pairs of gears to the shaft 44, there 60 are provided clutches 49 and 50, splined on the shaft 44 and having teeth at their tops and bottoms, to engage corresponding teeth in the inner sides of the bevel gears. The clutches 49 and 50 are so connected that 65 they can be operated concomitantly with the

operation of the clutches 22 and 23, so as to cause a simultaneous action of the tens-carrying mechanism with the master wheel mechanism, and for the purpose of accomplishing the same character of computation. 70 To this end the shift levers 25 and 26, which are pivoted at 51 and 52, have secured thereto pivot pins 53 and 54, on which are mounted supplementary shifting levers 55 and 56. These supplementary shifting 75 levers 55 and 56 have pins 57, which engage in grooves in the clutches 49 and 50, so as to form a positive connection which will permit a rotation of the clutches. A limited motion between the supplementary shifting 80 levers 55 and 56 and the main shifting levers 25 and 26 is provided by the supplementary levers being pivotally mounted on the main levers, and having fingers 58 and 59 extending on opposite sides of the pivots 85 51, at a certain distance, to permit a certain amount of play before positive connecting contact therewith. The play between the main and supplementary shifting 90 levers is taken up by springs 60 secured to the pins 53 and 54 and to the supplementary levers 55 and 56. The shaft 44 obtains its drive from the shaft 4 by being provided with a bevel gear 61 meshing with a gear 62 on a shaft 63, which has a bevel gear 64 95 meshing with a gear 65 on the shaft 4.

We now come to the mechanism which is used to obtain a predetermined sequence of operations by the computing heads, in an automatic manner, by the simple shifting 100 of a hand actuator. Arranged in juxtaposition to the shift levers 25 and 26, there is provided a control shaft 66, which is supported so as to be capable of having both an endwise reciprocating movement and a 105 rotary movement. Adjacent each of the shifting levers 25 and 26, the control shaft 66 is provided with setters 67 and 68, shown in the form of collars normally held in their lowermost position by means of 110 springs 69. These collars are provided with circular flanges 70 which overlie pins 71 and 72 secured to the shift levers 25 and 26, so that when the shaft 66 is depressed, these flanges will engage the pins 71 and 72, and force the shifting levers 25 and 26 to their lowermost position corresponding to adding. 115

Underlying each of the setters 67 and 68 there is provided a holder 73, which is shown in detail in Fig. 6 as provided with a series of radial slots 74 formed in a circular flange extending from the body portion of the holder. These slots are capable of receiving control tappets 75, one of which is shown in detail 120 in Fig. 10. The tappets 75 are preferably reduced at the point where they enter the slots 74, so as to prevent movement in a vertical direction of the tappets relative to their holder. That is to say, the tappets are 125 130

provided with grooves in their sides forming shoulders which engage the circular flange projecting from the body portion of the holder. In order to secure these tappets 5 in position on the holder, so that they may not slip off by accident, in a radial direction, they are provided with grooves 76 in which a circular detent 77 may enter. This detent is slidingly mounted on the shaft 66, and 10 normally held in its engaging position by a spring 78 which abuts against a collar 79 secured to the shaft 66 as well as against the detent 77. A portion of the outer surface of the detent 77 may be roughened or 15 knurled so as to permit it to be more readily handled.

It will be seen, by reference to Figs. 9 and 10, that the extreme top and bottom limits of the tappets 75 are located at 20 equal distances from the grooves provided in the sides of the tappets, so that if a tappet is reversed in the holder, it will project a different extent above the circular flange of the holder than it did before. The extent 25 of projection of a tappet above the flange of a holder determines the extent to which it will shift the corresponding shifting lever 25 or 26 from an adding position. In order that the tappets may be used in either position, they are provided with the grooves 30 76 at both their top and bottom so that the detent 77 will hold them in either position. The tappets may also be interchanged one with the other.

It will be seen that if one of the tappets is located beneath one of the pins 71 or 72, when the shaft 66 returns to its normal raised position, that it will shift this pin, and thus the shifting lever to which it is 35 secured, a given distance according to whether the larger or smaller end of the tappet is located above the flange of the holder. If the smaller end of the tappet, corresponding to the top end shown in Fig. 10, is located 40 uppermost, the shifting lever will be only moved back to a neutral position. If, however, the larger end of the tappet, corresponding to the lower end in Fig. 10, is at the 45 top, it will force the lever up to its extreme movement corresponding to a subtracting 50 position. Of course, if at any particular point a tappet is omitted, the lever will be allowed to remain in its lowermost position corresponding to adding.

It will thus be seen that, by arranging the controlling tappets around the holder, and giving the holder a combined movement, such that it will bring the tappets successively in operative contact with the pins 71 55 and 72, any predetermined sequence of operations of the computing heads may be obtained. In Fig. 12, a development of one arrangement of tappets in the holder is shown. Taken from left to right, the first 60 tappet will force the shifting lever to a

subtracting position, the second tappet to a neutral position, lack of a tappet in the third place will leave it at an adding position, and so on.

In order to obtain a reciprocating, rotary motion of the shaft 66, necessary to successively operate the shifting levers 25 and 26 together with the supplementary levers operated thereby, the shaft 66 is provided, adjacent its lower end, with a grooved shifting collar 80, engaged by a rocker 81 shown in the form of a bell crank lever, having one arm 82 rounded to form a follower which will engage the sides of a cam slot 83 provided in an actuator 84, shown in the form of a lever mounted to rotate loosely on a collar 85 splined on to the shaft 66. The actuator 84 is normally held in its unactuated position, corresponding to that shown in Fig. 4, by means of a spring 86. The actuator 84 is not only used to reciprocate the shaft 66, but also to rotate this shaft. This is accomplished by means of a spring-pressed pawl 87 pivotally mounted on the actuator 84, and adapted to engage the teeth of a ratchet wheel 88 splined on the shaft 66. The ratchet wheel 88, and thus the shaft 66, is prevented from backward rotation by means of a spring-pressed detent or dog 89.

The relation of the pawl 87 with the ratchet wheel, as shown in Fig. 4, is such that there will be an appreciable swing of the actuator 84 before it starts to rotate the shaft 66, by engagement with one of the teeth of the ratchet wheel 88. This ineffective throw or play of the actuator is taken advantage of to slide the shaft 66 down to its lowermost position. To accomplish this result, the cam slot 83 from the beginning, indicated at 90, to a point, (see Fig. 5) 100 changes rather abruptly so as to swing the follower 82 from its innermost to its outermost position, whereby the shaft 66 will be drawn from its uppermost position to its lowermost position, that is to say, from the 105 position shown in Fig. 2 to the position shown in Fig. 3. For the remainder of the stroke of the actuator 84, the pawl 87 engages a tooth of the ratchet wheel 88 just long enough to bring the next slot 74 in the 110 holders 73 underneath the pins 71 and 72. If this slot contains a tappet, the pin or pins will be shifted to a position corresponding to either neutral or subtracting. If the slots do not contain tappets, the pins will remain 115 at the adding position. During this latter part of the initial stroke of the actuator 84, the follower 82 is substantially unactuated, because of the fact that the remainder of the cam slot 83 is substantially circular, with the axis of the shaft 66 as a center.

The actuator 84 is automatically thrown back by the spring 86, so as to return to the position shown in Fig. 4. During this movement this cam slot 83 travels so as to leave 120

the follower unactuated until the actuator has almost reached its normal position, and then, for the last fraction of the return stroke, shifts the shaft 66 back up into its 5 normal position so that whatever tappets are beneath the pins 71 and 72, they will engage the same and shift the levers to which they are connected to the positions corresponding to the tappets.

10 To avoid danger of the typist throwing the actuator a fraction of a stroke, there is provided a two-way acting lock 92, which is of such a character that the actuator must be swung its full stroke in one direction before it will be permitted to return, and also 15 so that the actuator cannot be partially returned and then swung out again. In this case this two-way lock is shown in the form of a two-way ratchet bar 93 engaged by a 20 pawl 94 pivotally mounted on the actuator 84 in such a manner that it can swing to either side of its pivot, and when in engagement with the ratchet bar 93 will prevent a return of the actuator until the pawl has 25 traveled over the full length of the ratchet bar. The pawl 94 is held by a spring 95, which is so arranged that it will cause the pawl to engage the ratchet bar positively in whichever direction the actuator 84 is traveling.

30 When the automatic hand mechanism is in operation it is desirable to relieve it of any unnecessary retarding action or friction. It therefore may be advisable to remove the 35 latches 27 and 28 from engagement with the notches 29. For this purpose, there is provided a throw-off 96, shown in detail in Fig. 8, which is slidingly mounted by means of one or more pin-and-slot connections 97, and 40 is shown in the form of a bar 98 having an operating handle 99 extending from one side thereof and a plurality of arms 100, one for each of the latches 27, which underlie the same and are adapted to lift said latches 45 from engagement with said notches 29, when the throw-off is moved to its uppermost position. The throw-off 96 may be held in either position of adjustment by a spring catch 101, which engages any one of a plurality 50 of notches 102 provided in the edge of the bar 98.

55 In the operation of the device, the action or position tappets 75 are placed around each of the holders 73, according to the successive operations which it is desired that each computing head shall perform, thereby forming a controller which governs the action of each computing head. For example, if we take the upper computing head, 60 by referring to Fig. 12 where a controller is developed, it will be seen that the first tappet, starting at the left, is arranged with its largest end up, so as to shift the clutches to their subtracting positions corresponding to 65 the subtracting direction of rotation of both

the master wheel and the tens-carrying mechanism. The second tappet will not shift the clutches quite so far, inasmuch as its smaller end is above the flange of the holder, so that it will correspond to a neutral position of both of the clutches, and thus neither the master wheel nor the tens-carrying mechanism will be driven. The third slot of the holder is shown to be vacant, so that the clutches after having been 70 shifted to their adding positions will not be returned but remain in their adding positions, thus causing the master wheel and the tens-carrying mechanism to rotate in an adding direction. The remainder of the 75 slot positions of the holder are shown to have, successively, tappets or no tappets, corresponding respectively to subtracting, subtracting, neutral, adding and neutral.

80 The tappets are formed so that they can 85 be reversed and interchanged in the holder, and thus are capable of acting to control the mechanism for either subtracting or neutral, and by omitting the tappets, the adding state of the computing heads can be 90 obtained. This, it will be seen, enables the tappets to be made exactly alike, and simplifies the use of the same.

95 After the tappets have been properly placed according to the predetermined sequence of operations desired, the typist can then perform the combined operation of inscribing the figures upon the work sheet and computing said figures in the computing head by striking numeral keys (not 100 shown) so that the master wheels are given a predetermined rotation of an extent dependent upon the particular numeral keys struck, this, however, only happening if the master wheel is connected in driving relation 105 with the shaft 66 by having the clutches either in their adding or subtracting position. If we start with the computing heads, each performing a certain operation, it is merely necessary for the typist to swing the 110 actuator 84 a complete stroke in order to bring all of the computing heads to their next state. By swinging the actuator 84 the follower 82 is first shifted from the position indicated in Fig. 2 to the position 115 indicated in Fig. 3, whereby the rocker 81 will be swung so as to pull down the shaft 66 from the position shown in Fig. 2 to the position shown in Fig. 3. During this time the pawl 87 has been moving from the position shown in Fig. 4 to the position shown in Fig. 5, so that it has not as yet actuated the ratchet wheel 88 to rotate the shaft 66. This permits the tappets to be withdrawn 120 from any possibility of engagement with pins 71 and 72 while the shaft is being rotated. The rotation is accomplished by the pawl 87 engaging the tooth with which it is in opposition in Fig. 5, so that the next slots in the holder 73, whether they contain tap- 130

5 pets or not, will be brought underneath the pins 71 and 72. During this portion of the movement of the actuator 84, the follower 82 will remain stationary, inasmuch as the slot 83 does not change relative to the shaft 66 for this distance. The lock 92 will force the typist to throw the actuator 84 a complete stroke before said actuator can be returned.

10 During the return motion of the pawl 87, it is withdrawn out of positive engagement with the tooth on the ratchet wheel 88, and then the shaft 66 is thrown up to its uppermost position by the follower 82, changing 15 from the upper portion of the cam slot 83 to the inner portion. When the shaft has been moved to its lowermost position, the setters 67 have engaged the pins 71 and 72, so as to swing the shifting levers 25 and 26 20 and the clutches operated thereby to their adding positions, so that when the shaft 66 returns to its uppermost position, it will shift these pins separately, or not, according to whether or not there are tappets under 25 the pins at this particular position of rotation of the shaft 66. If there is no tappet beneath either of the pins the corresponding computing head will remain in its adding state. If there is a tappet with a short end 30 uppermost, the corresponding computing head's clutches will be shifted to a neutral position, leaving the computing head inactive. If the larger end of the tappet is uppermost, beneath a pin, it will shift the 35 clutches to their subtracting position, so that the corresponding computing head will now be actuated, so as to subtract the numeral struck subsequently by the typewriting keys. The operation of the actuator may be re- 40 peated as often as the typist desires to change the character of work carried on by the computing mechanism.

Certain features disclosed herein are broadly claimed in my co-pending application, Serial No. 569,502, filed June 29, 1910, 45 which application is directed, among other things, to the feature of the provision of a series of state-controlling cams or the like upon a revoluble controller, and also to the 50 feature of shifting said controller to silence the same, and of bringing into use other controllers for individually determining the state of the totalizers. The claims in this application are restricted to features not dis- 55 closed in said application No. 569,502.

Variations may be resorted to within the scope of the invention, and portions of the improvements may be used without others.

Having thus described my invention, I 60 claim:

1. The combination with a computing head capable of adding and subtracting, of a controlling mechanism for selecting the character of work carried on by said computing

head, said controlling mechanism including 65 a tappet having both a positioning movement and an actuating movement to control said computing head, and a device for imparting to said tappet both movements.

2. The combination with a computing 70 head capable of adding and subtracting, of controlling mechanism for selecting the character of work to be carried on by said computing head, said controlling mechanism including a plurality of tappets having both 75 a positioning movement and an actuating movement to control said computing head, said actuating movement being uniform for all of said tappets, and the tappets having different effective magnitudes whereby to 80 differently control said computing head on said uniform actuating movement, and a device for imparting to said tappets both movements.

3. The combination with a computing 85 head capable of adding and subtracting, of a controlling mechanism for selecting the work carried on by said computing head, said controlling means including a plurality of tappets having a positioning movement and also an actuating movement to control said computing head, said tappets being interchangeable with each other, and so formed that their effect is different on said actuating movement in one position of adjustment from what it is in another position.

4. The combination with a computing head capable of adding and subtracting, of a controlling mechanism for selecting the work carried on by said computing head, 100 said controlling mechanism including a plurality of tappets, means for giving said tappets movement to successively position one tappet at a time, said means also acting to give all of said tappets an actuating movement whereby said positioned tappet will actuate said controlling mechanism for selecting the work to be carried on by said computing head.

5. The combination with a computing 110 head capable of adding and subtracting, of a controlling mechanism for selecting the work carried on by said computing head, said controlling mechanism including a tappet having a positioning movement and also 115 an actuating movement to control said computing head, said tappet being reversible so that on said actuating movement the effect of said tappet is greater in one position than in the other position.

6. The combination with a computing head capable of performing a plurality of different types of computations, of a controlling mechanism for selecting the work carried on by said computing head, said controlling mechanism having a plurality of tappets, and said tappets being of different effective magnitudes at their opposite ends.

7. The combination with a computing head capable of performing a plurality of different types of computations, of a controlling mechanism for selecting the work carried on by said computing head, said controlling mechanism having a plurality of tappets, and said tappets being of different effective magnitudes at their opposite ends, and also being reversible to vary their effect.
10. 8. The combination with a plurality of computing heads, each capable of inaction and action in a plurality of different ways to perform a number of different types of computation, of individual controlling mechanism for each computing head for determining the action of each head, said controlling mechanism having a plurality of successively effective tappets, and a single actuator for successively operating all of said controlling mechanisms simultaneously to successively control said computing heads.
15. 9. The combination with a plurality of computing heads, of individual means for controlling the state of action of each computing head, latches for each of said individual means, for maintaining said means in any position of adjustment, a single actuator for controlling concomitantly all of said means, a throw-off for rendering said 20 latches inoperative while said actuator is in operation, said throw-off comprising a slideable bar, a handle for manipulating said bar, and a plurality of arms connected to said bar and extending under said latches.
25. 10. The combination with a computing head capable of inaction and action to perform a variety of computations, of means for changing the action of said computing head, rotary reciprocating means for governing said first-mentioned means, and an actuator for manipulating said rotary reciprocating means for its rotating and reciprocating movement.
30. 11. The combination with a computing head capable of inaction and action to perform a variety of computations, of means for changing the action of said computing head, rotary reciprocating means for governing said first-mentioned means, an actuator for manipulating said rotary reciprocating means for its rotating and reciprocating movement, and a spring for returning said actuator and also acting on said rotary reciprocating means.
35. 12. The combination with a computing head capable of a plurality of states of action and inaction, of means for controlling the action of said computing head, rotary reciprocating means for governing said first-mentioned means, and an actuator for alternately reciprocating and rotating said last-mentioned means.
40. 13. The combination with a computing head, of means for determining the state of said computing head, a member positionable to control said determining means and also movable to engage and move said determining means, and means for preventing the engaging and moving movement until said positioning movement has been effected.
45. 14. The combination with a computing head, of means for determining the state of said computing head, a member adapted to be rotatable in one plane to a position to control said determining means, and moved in another plane to engage and move said determining means, and means for preventing said last mentioned movement until said rotary movement has been effected.
50. 15. The combination with a computing head, of means for determining the state of said computing head, a controller to be operated to move said determining means to a predetermined point, to be then positioned to control said determining means, and to be then moved when so positioned to move said determining means to some other point, and means for preventing the third said movement of said controller until the second said movement has been effected.
55. 16. The combination with a computing head, of means for determining the state of said computing head, a controller to be operated to move said determining means to a predetermined point, to be then positioned to control said determining means, and to be then moved when so positioned to move said determining means to some other point, a reciprocating actuator for said controller, acting on the first part of its initial stroke to operate said controller to its first position, on the last part of its initial stroke to operate said controller to its second position, and on its return stroke to operate said controller to its third position, and means for preventing the third said movement of said controller until said second movement has been effected, comprising a full stroke device acting on the last part of the initial stroke of said actuator.
60. 17. The combination with a computing head capable of a plurality of states of action and inaction, of shifting means for determining the state of said computing head, controlling means for governing the position of said shifting means, and thereby the state of said computing head, and an actuator for manipulating said controlling means, said actuator reciprocating and rotating said controlling means at different times.
65. 18. The combination with a computing head capable of a plurality of states of action and inaction, of shifting means for determining the state of said computing head, controlling means for governing the position of said shifting means, and thereby the state of said computing head, and an actuator for manipulating said controlling means.

- means, said actuator reciprocating and rotating said controlling means at different times, said actuator causing a complete reciprocation of said controlling means and a 5 partial rotation thereof.
19. The combination with a computing head capable of a plurality of states of action and inaction, of shifting means for determining the state of said computing head, 10 controlling means for governing said shifting means, and an actuator for manipulating said controlling means, said controlling means including a shaft and a plurality of tappets carried by said shaft, and said actuator acting to remove one of said tappets from active engagement with said shifting means and bring another of said tappets in active engagement with said shifting means.
20. The combination with a computing head capable of a plurality of states of action and inaction, of shifting means for determining the state of said computing head, 15 controlling means for governing said shifting means, and an actuator for manipulating said controlling means, said controlling means including a shaft and a plurality of tappets carried by said shaft, and said actuator acting to remove one of said tappets from active engagement with said shifting means and bring another of said tappets in active engagement with said shifting means; certain of said tappets being arranged to have different effects than certain others of 20 said tappets.
21. In a combined typewriting and computing machine, the combination with a carriage, of a computing head capable of a plurality of states of action and inaction, shifting means for determining the state of said 25 computing head in the different zones or columns determined by said carriage, a control shaft, tappets carried by said control shaft, and a manually operated actuator for bringing each of said tappets successively into cooperation with said shifting means, independently of the position of the carriage.
22. The combination with a computing head, of shifting means for determining the state of said computing head, controlling 30 means for governing said shifting means, said controlling means acting, at each operation, to manipulate said shifting means to a predetermined position, and also capable of acting to leave said shifting means at 35 said predetermined position or else move said shifting means to any one of a plurality of points at variable distances from said predetermined position, said controlling means embodying a shaft and a plurality of tappets, arranged for different effects, carried by said shaft, and an actuator for reciprocating said shaft, and causing a partial rotation thereof at each reciprocation.
23. The combination with a computing 40 head, of shifting means for controlling the state of said computing head, a shaft, a holder on said shaft, and a plurality of removable tappets carried by said holder for governing the control of said computing head by said shifting means.
24. The combination with a computing head, of shifting means for determining the state of said computing head, a shaft, and a plurality of interchangeable tappets of different effects brought successively into 45 coöperation with said shifting means by the movement of said shaft, to govern the control of said computing head by said shifting means.
25. The combination with a computing 50 head, of shifting means for determining the state of said computing head, a shaft, and a plurality of reversible tappets brought successively into coöperation with said shifting means by the movement of said shaft, to determine the control of said computing head by said shifting means.
26. The combination with a computing head, of means for determining the state of said computing head, a shaft, a holder carried by said shaft, said shaft being movable to a plurality of predetermined positions, said holder having a plurality of points corresponding to the positions of said shaft, and one or more removable tappets 55 mounted on said holder at one or more of said points, to control the action of said means.
27. The combination with a computing head, of means for determining the state of said computing head, a shaft, a holder carried by said shaft, said shaft being movable to a plurality of predetermined positions, said holder having a plurality of points corresponding to the positions of said shaft, and one or more tappets mounted on said 60 holder at one or more of said points, to control the action of said means; said tappets being reversible to change their effect.
28. The combination with a computing 65 head, of means for determining the state of said computing head, a shaft, a holder carried by said shaft, said shaft being movable to a plurality of predetermined positions, said holder having a plurality of points corresponding to the positions of said shaft, and one or more tappets mounted on said holder at one or more of said points, to control the action of said means; said tappets being detachably connected to said 70 holder.
29. The combination with a computing head, of means for determining the state of said computing head, a shaft, a holder carried by said shaft, said shaft being movable to a plurality of predetermined positions, said holder having a plurality of points corresponding to the positions of said 75 holder.

5 said shaft, one or more tappets mounted on said holder at one or more of said points, each of said tappets having a head portion to control the action of said means; each of 10 said tappets also having a groove in said head portion, and a detent engaging said groove to secure said tappets in position on said holder.

10 30. The combination with a computing head, of means for determining the state of said computing head, a shaft, a holder carried by said shaft, said shaft being movable to a plurality of predetermined positions, said holder having a plurality of 15 points corresponding to the positions of said shaft, one or more tappets adjustably mounted on said holder at one or more of said points, each of said tappets having a head portion to control the action of said means; each of said tappets also having a 20 groove in said head portion, and a circular spring-pressed detent for engaging said groove to secure said tappets in position on said holder.

25 31. The combination with a computing head, of means for determining the state of said computing head, a shaft, a holder carried by said shaft having a flange with a plurality of slots therein, and a plurality 30 of tappets positively movable in one direction for governing the control of said computing head by said means, said tappets engaging said flange so as to be held in said slots for such movement.

35 32. The combination with a computing head, of means for determining the state of said computing head, a shaft, a holder carried by said shaft having a flange with a plurality of slots therein, and a plurality 40 of tappets, positively movable in one direction for governing the control of said computing head by said means, each of said tappets having a groove therein, said groove holding said tappets for such movement by 45 engagement of said flange therewith.

50 33. The combination with a computing head, of means for determining the state of said computing head, a shaft, a holder carried by said shaft having a flange with a plurality of slots therein, and a plurality of 55 tappets, for governing the control of said computing head by said means, located in certain of said slots, each of said tappets having a groove therein, to determine the position of each tappet on said holder; said tappets being of different effective magnitudes on opposite sides of said groove to thereby differently control said determining means.

60 34. The combination with a computing head, of means for determining the state of said computing head, a shaft, a holder carried by said shaft having a flange with a plurality of slots therein, and a plurality

65 of tappets, for governing the control of said computing head by said means, located in certain of said slots, each of said tappets having a groove on each side of a center line and symmetrically located in respect to said line to determine the position of 70 each tappet on said holder; said tappets being of different effective magnitudes on opposite sides of said groove to thereby differently control said determining means; and being reversible in said slots to present 75 either end to said determining means.

35. The combination with a computing head, of means for determining the state of said computing head, a shaft, a holder carried by said shaft having a flange with 80 a plurality of slots therein, a plurality of tappets positively movable in one direction for governing the control of said computing head by said determining means, a spring-pressed detent for detachably securing said tappets in said holder, each of said tappets having a groove adapted to be engaged by the flange of said holder to secure said tappet for positive movement, said tappet also having a head portion to engage 90 said determining means, and a groove in said head portion adapted to be engaged by said spring-pressed detent.

36. In a combined typewriting and computing machine, the combination with a carriage, of a computing head, means for determining the state of said computing head in different zones or columns determined by said carriage, a setter movable to engage 100 said state determining means and to move said means to a predetermined point, and a manually operable controller for determining in any zone whether said state determining means shall remain at said predetermined point or be manipulated to any one of a plurality of other points; said controller including a plurality of members of variable effect.

37. In a combined typewriting and computing machine, the combination with a carriage, of a computing head, means for determining the state of said computing head in different zones or columns determined by said carriage, a setter movable to engage 110 said state determining means and to move said means to a predetermined point, and a manually operable controller for determining in any zone whether said state determining means shall remain at said predetermined point or be manipulated to any one of a plurality of other points; said controller including a plurality of members of variable effect, and an actuator for manipulating said controller at each operation thereof, to change the position of said members.

38. The combination with a computing head, of means for determining the state of

- said computing head, a shaft, a tappet carried thereby, a rocker, a cam, and an actuator, said actuator acting through the medium of said cam, rocker and shaft to move 5 said determining means to a predetermined point, said actuator also acting through the medium of said shaft and tappet to control the movement of said determining means to some other point.
- 10 39. The combination with a computing head, of means for determining the state of said computing head, a shaft, a tappet carried thereby, means for rotating said shaft, and a lever, said lever acting through 15 the medium of said shaft to move said determining means to a predetermined point, said lever also acting through said rotating means to position said tappet to control the movement of said determining means.
- 20 40. The combination with a computing head, of means for determining the state of said computing head, a shaft, a tappet carried thereby, means for rotating said shaft, a cam, a rocker controlled thereby, 25 and a lever, said lever acting through the medium of said shaft, rocker and cam for moving said determining means to a predetermined point, and acting through the medium of said rotating means and shaft 30 for positioning said tappet to control said determining means.
41. The combination with a computing head, of means for determining the state of said computing head, a shaft, tappets 35 carried by said shaft for governing the action of said means, a lever loosely mounted with respect to said shaft and having a cam surface thereon, a rocker having a follower engaging said cam surface, said
- 40 rocker being connected to said shaft so that a manipulation of said lever will swing said rocker to reciprocate said shaft, to move said determining means to a predetermined point, and means for rotating said shaft by 45 said lever whereby said lever will position a tappet to control said determining means, said cam surface and said rotating means being so arranged that their effective action will take place at different times.
- 50 42. The combination with a computing head, of means for determining the state of said computing head, a shaft, a spring for said shaft, a rocker engaging said shaft, a lever acting through the medium of said 55 rocker to move said shaft against the tension of said spring to move said determining means to a predetermined point, a cam moved by said lever and positively controlling said rocker, and a spring acting on 60 said rocker through the medium of said cam to return said lever and assist said first-mentioned spring to return said shaft to normal position.
43. The combination with a computing

head, of means for determining the state 65 of said computing head, a shaft, means carried by said shaft for governing the action of said means, a lever loosely mounted with respect to said shaft and having a cam surface thereon, a rocker having a follower 70 engaging said cam surface, said rocker being connected to said shaft so that a manipulation of said lever will swing said rocker to reciprocate said shaft to move said determining means to a predetermined point, 75 means for rotating said shaft by said lever to position the means carried thereby to control said determining means, said cam surface and said rotating means being so arranged that their effective action will take 80 place at different times, and a lock for preventing an opposite motion of said lever before a complete stroke in one direction and acting during the actuation of said rotating means only. 85

44. The combination with a computing head, of means for determining the state of said computing head, a shaft, controlling means on said shaft for governing said first-mentioned means, a lever mounted to rotate 90 with respect to said shaft, a one-way clutch connection between said lever and said shaft, whereby said lever may rotate said shaft, said lever having a cam surface thereon, a rocker connecting said cam surface with said 95 shaft, whereby a manipulation of said lever may reciprocate said shaft, said cam surface being concentric with said shaft for a portion of its extent, so as to permit a rotation of said shaft while said shaft is free from 100 longitudinal movement.

45. The combination with a computing head, of means for determining the state of said computing head, a shaft, controlling means on said shaft for governing said first-mentioned means, a lever mounted to rotate 105 with respect to said shaft, a one-way clutch connection between said lever and said shaft, whereby said lever may rotate said shaft, said lever having a cam surface thereon, a 110 rocker connecting said cam surface with said shaft, whereby a manipulation of said lever may reciprocate said shaft, said one-way clutch having a limited ineffective play, to permit a reciprocation of said shaft by said lever through the intermediary of said cam surface and said rocker, while said shaft remains free from rotary movement. 115

46. The combination with a computing head, of means for determining the state of 120 said computing head, a shaft, controlling means on said shaft for governing said first-mentioned means, a lever mounted to rotate with respect to said shaft, a one-way clutch connection between said lever and said shaft, whereby said lever may rotate said shaft, said lever having a cam surface thereon, a 125 rocker connecting said cam surface with said

- shaft, whereby a manipulation of said lever may reciprocate said shaft, said cam surface being concentric with said shaft for a portion of its extent, so as to permit a rotation 5 of said shaft while said shaft is free from longitudinal movement, said one-way clutch having a limited ineffective play, to permit a reciprocation of said shaft by said lever through the intermediary of said cam surface and said rocker, while said shaft remains free from rotary movement. 10
47. The combination with a plurality of computing heads, a setting member for each of said computing heads for concomitantly changing the state of each head, a shaft, a series of tappets for each of said members, carried by said shaft, for manipulating said members in the opposite direction variable extents according to the effective magnitude 15 of the active tappets, and a single actuator for manipulating all of said tappets, and bringing each of said tappets successively into its active position. 20
48. The combination with a computing head, of means for determining the state of said computing head, a plurality of tappets, a manually operable lever, and means controlled from said lever for bringing said tappets successively into position for operating 25 on said state-determining means. 30
49. The combination with a computing head capable of existing under a plurality of states as to adding, subtracting and remaining neutral, of manual means adapted to be successively operated, and means controlled from said manual means for varying the state of said computing according to a predetermined sequence at each successive operation. 35
- 40 50. The combination with a computing head capable of existing under a plurality of states as to adding, subtracting and remaining neutral, of manual means adapted to be successively operated, and means for insuring a complete change in state at each successive movement of said manual means, comprising a lock acting on said manual means during a part of its stroke only. 45
51. In a computing mechanism, a tappet having means by which it may be supported, said means being located at unequal distances from the ends thereof, said tappet acting on said computing mechanism to variably affect it according as said tappet is 55 differently supported. 50
52. The combination with a computing head, of a shifting lever for controlling the state of said computing head, a pin on said shifting lever, a uniform collar engaging 60 said pin for shifting it in one direction, and a series of tappets having different features for engaging said pin to shift it in the opposite direction. 65
53. In a computing mechanism, a locking 70
- detent having an annular engaging surface to lock a series of tappets in position on their holder, each of said tappets having a head portion to control said computing mechanism and a groove in said head portion to be engaged by said detent. 75
54. The combination with a computing mechanism, said computing mechanism being capable of existing under a plurality of states as to the activity and type of computation carried on thereby, of a carriage connected to determine different computing zones or columns, and means operable at will at any part of the travel of said carriage for varying the state of said computing mechanism according to a predetermined sequence. 80
55. The combination with a computing mechanism capable of existing under a plurality of states as to activity and the type of activity carried on thereby, of a carriage traveling to determine different computing zones or columns, and manual means for varying at will the state of said computing mechanism successively and according to a predetermined sequence, so that the sequence of state may correspond to any desired sequence of zones. 85
56. The combination with a computing head, of gearing for driving said head, a shifting mechanism for determining the drive and character of drive of said head by said gearing, a setter for manipulating said shifting mechanism, and a series of tappets having their ends facing said setter, located at variable distances therefrom and arranged to actuate said shifting mechanism 90 in a direction opposite to that of the actuation of said setter. 95
57. The combination with a computing head, of gearing for driving said head, a shifting mechanism for determining the drive and character of drive of said head by said gearing, a setter for manipulating said shifting mechanism, and a series of tappets having their ends facing said setter, located at variable distances therefrom and arranged 100 to actuate said shifting mechanism in a direction opposite to that of the actuation of said setter, said tappets being adjustable to vary the clearway between the ends thereof and said setter. 110
58. The combination with a computing mechanism variable as to its action, of controlling mechanism for varying the action of said computing mechanism, said controlling mechanism including a holder having a series of spaced receiving points, and a series of spaced tappets of variable effect located at some of said points. 115
59. The combination with a computing mechanism capable of existing under a plurality of states, of a traveling carriage arranged to determine the periods of activity of said computing mechanism, and a rota- 120
- 125

table controlling mechanism rotatable by hand at the will of the operative, and at any point in the travel of said carriage, to cause a sequence of states of said computing mechanism.

60. The combination with a computing mechanism capable of existing under a plurality of states, of a traveling carriage arranged to determine the periods of activity of said computing mechanism, and a rotatable controlling mechanism rotatable by hand at the will of the operative, and at any point in the travel of said carriage, to cause a sequence of states of said computing mechanism according to a predetermined plan.

61. The combination with a plurality of individual computing sets, of a plurality of controlling mechanisms, one individual to each computing set for determining the states of the accordant sets, each of said controlling mechanisms including a plurality of separate and distinct determining members, corresponding each to the particular state which it institutes in the accordant computing set, and a common means for controlling said determining members.

62. The combination with a computing mechanism capable of existing under a plurality of different states, of a shifting mechanism for determining the state of said computing mechanism, and controlling mechanism for actuating said shifting mechanism including a plurality of exactly similar tappets positioned so as to have different effects.

63. The combination with a computing mechanism capable of existing under a plurality of different states, of a shifting mechanism for determining the state of said computing mechanism, and controlling mechanism for actuating said shifting mechanism including a plurality of exactly similar tappets positioned so as to have different effects, said tappets being readjustable so as to vary their effect.

64. The combination with a plurality of individual computing mechanisms, of a state-controlling mechanism individual to each computing mechanism, and driving means common to all of said controlling mechanisms for driving said controlling mechanisms in unison, each of said controlling mechanisms being individually adjustable so as to vary the individual effect independently of the other controlling mechanisms.

65. The combination with a computing mechanism, of controlling mechanism for governing the state of said computing mechanism, said controlling mechanism having a rotary movement and a reciprocating movement, both movements being necessary to effective change in state of said computing mechanism, means for reciprocating said

controlling mechanism while said mechanism is silent as to its rotary movement and means for rotating said controlling mechanism while said mechanism is silent as to its reciprocating movement.

66. The combination with a computing mechanism for computing in a cycle of several computing zones, of a state-controlling mechanism having a series of successive step-by-step movements aggregating in all a cycle of operation corresponding step for zone with the cycle of zones of said computing mechanism, and having a configuration corresponding at different points in the movement thereof to a variety of states or characters of computation of said computing mechanism, said state-controlling mechanism having its parts adjustable so as to change the configuration and thus the character of computation for different computing zones or steps in a cycle of movement thereof, so as to accord any state with any zone, and whereby any sequence of states may correspond to any sequence of zones.

67. The combination with a computing device, of a manually operable handle, a controlling mechanism including a tappet device, said tappet device movable to determine the state of the computing device, and means operable by similar movements of said handle to move said tappet device to different predetermined positions.

68. The combination with a computing head, of means for determining the state of said computing head, a plurality of tappets for controlling said determining means, a manual lever, and means brought into action by movements of said lever to bring the tappets successively into a position to control said determining means and to move said determining means through the medium of the tappet so positioned.

69. The combination with a computing head and means for determining the state of said computing head, of a tappet, a manual lever, means brought into action on a movement of said lever to move said tappet to a position to control said determining means, and means brought into action on another movement thereof to move the tappet so positioned to move said determining means.

70. In a computing machine the combination with computing mechanism, a carriage traveling to determine different computing zones or columns and a device movable from one position to another in accordance with said zones or columns, and determining while stationary in its different positions, different states under which said computing mechanism may exist in the different zones or columns determined by said carriage.

71. In a computing machine the combination with computing mechanism including

a plurality of computing heads, of a carriage traveling to determine different computing zones or columns, and a controlling device, one for each computing head, said controlling devices movable from one position to another in accordance with different zones or columns and determining while stationary in their different positions, different combinations of state under which said computing mechanism may exist in the 10 different zones or columns determined by said carriage.
